UNITED STATES PATENT OFFICE.

ALONZO LOBDELL, OF RACINE, WISCONSIN.

ATTACHMENT FOR BRIDLE-BITS.

SPECIFICATION forming part of Letters Patent No. 449,163, dated March 31, 1891.

Application filed June 17, 1890. Serial No. 355,737. (No model.)

To all whom it may concern:

Be it known that I, ALONZO LOBDELL, of Racine, in the county of Racine, and in the State of Wisconsin, have invented certain new and useful Improvements in Attachments for Bridle-Bits; and I do hereby declare that the following is a full, clear, and exact description thereof.

My invention relates to attachments for bridle-bits; and the invention consists in certain peculiar and novel features of construction and arrangement, as hereinafter described, and pointed out in the appended claims.

15 In order that my invention may be fully understood, I will proceed to describe it with reference to the accompanying drawings, in which—

Figure 1 is a rear elevation of a harness-bit with my improved attachment applied thereto. Fig. 2 is a transverse section on the line 2 2 of Fig. 1. Fig. 3 is a side elevation of my attachment applied to a harness-bit with the ring of the bit and the bridge-pieces shown in section. Fig. 4 is a sectional view of a modified form of my attachment applied to the ring of a harness-bit, the outer part of the latter being shown in cross-section.

The object of my invention is to provide an attachment for any usual or preferred form of harness-bit which shall be simple and durable in construction and easily applied to the bit and by means of which "hard-mouthed" horses can be instantly controlled by simply pulling upon the driving-reins. These results I attain by virtue of the construction which I will now proceed to describe.

Referring to the drawings, A designates the bar, and B the rings, of an ordinary driving-bit. The bit shown is provided with snaffles C, but the bit may be either a plain ring-bit, curb-bit, or any other preferred type.

D designates a cheek-plate, which is of L shape, the lower arm d of which is bent so as to extend across the lower side of the outer part of the ring B and is provided at its outer end with a loop d', to which the driving-rein is attached. Near to its point of juncture with the upper arm or cheek-piece D' this arm d is formed with an elongated longitudinal slot e for a purpose to be presently explained.

F F' designate two bridge-pieces, which are of elongated form and extend across the ring B above and below the same, respectively, as shown, so as to clamp said ring between them. The adjacent ends of these bridge-pieces are secured together by two screws f, which lie at opposite sides of the adjacent portion of ring B and firmly retain the bridge-pieces upon the latter. A bolt g passes through the middle of the bridge-pieces F F' and also through the slot e, before referred to, and is held by a nut g', as shown.

In Figs. 1, 2, and 3 the bridge-pieces F F' are shown as of considerable thickness and may be supposed to be castings, bosses h being shown as formed on the inner sides of said pieces to properly separate them. In Fig. 4, however, the bridge-pieces are shown as thinner and may be supposed to be steel plates. In this instance these plates are bent over the ring B and also over the part d of cheek-plate D, thus making a close fit upon said parts. In either of these forms a strong pull upon the rein will draw the arms d backward and press the arms D' against the horse's jaw, thereby perfectly controlling him, however unruly he may be disposed to act. The cheek-plates D D' are preferably of steel or malleable cast-iron, and also serve to prevent the bit from being pulled through the animal's mouth. In order to adjust these cheek-plates for different sizes or hardness of the animal's mouth, it is only necessary to loosen the nuts g' and move the pieces toward one or the opposite end of the slots e, as required, and then tighten up the nuts again.

Having thus described my invention, what I claim as new therein, and desire to secure by Letters Patent, is—

1. An improved attachment for bridle-bits, consisting of a pair of plates secured to each ring of the bit and a pair of L-shaped bars secured to said plates, the inner arms of said bars projecting parallel to the animal's jaws and the outer arms of said bars being bent and extending across the outer side of said rings, the extreme outer ends of the said bars being formed to receive the head ends of the driving-reins, substantially as set forth.

2. An improved attachment for bridle-bits, comprising an L-shaped bar having a slot in its lower arm and a pair of plates embracing

said arm and designed to embrace the ring of a bit, and a bolt or pin extending through the plates and slot, substantially as described.

3. The combination, with a bridle-bit, of a
5 pair of bridge-pieces embracing a ring of the
bit, and an L-shaped cheek-plate having its
lower arm secured adjustably between said
bridge-pieces, substantially as described.

In testimony that I claim the foregoing I
have hereunto set my hand, at Milwaukee, in
the county of Milwaukee and State of Wis-
consin, in the presence of two witnesses.

ALONZO LOBDELL.
